QUATERNARY AMMONIUM ENOLATES OF PSEUDO-ACIDS OF THE KETONIC TYPE

Reginald L. Wakeman, Philadelphia, Pa., and E Griffin Shay, Belle Mead, N.J., assignors, by mesne assignments, to Millmaster Onyx Corporation, New York, N.Y., a corporation of Delaware
No Drawing. Filed June 15, 1964, Ser. No. 375,352
6 Claims. (Cl. 260—286)

The object of the present invention is the preparation of microbiologically active compounds by reaction of certain quaternary ammonium salts with alkali-metal salts of pseudo-acids of the ketonic type.

The products of this invention conform, in general, to the following structure:

wherein Z is the cation of a microbiologically active quaternary ammonium compound; R is an alkyl or a halogenated alkyl group; R' is hydrogen, a halogen or an acyl group; and R'' is an alkyl or an alkoxy group.

Typical of these pseudo-acids are 2,4 pentanedione; 3-bromo-2,4 pentanedione; 1-phenyl-1,3 butanedione; 3-acetyl-2,4-pentanedione; 1-trifluoro-2,4 pentanedione; ethyl acetoacetate and the like. They are characterized in that they have an active hydrogen in the alpha position and in that they require an appreciable length of time to ionize.

Typical examples of the quaternary ammonium compounds which may be used in this invention are the alkyl trimethyl ammonium chlorides, alkyl-benzyl trimethyl ammonium chlorides, alkyl dimethyl benzyl ammonium chlorides, alkyl dimethyl menaphthyl ammonium chlorides, alkyl dimethyl substituted-benzyl ammonium chlorides in which the benzyl radical is substituted with one or more side chains containing from 1 to 5 carbon atoms such, for example, as methyl, dimethyl, ethyl and the like and in which the carbon atoms may all be in the same or different side chains or in which the benzyl radical bears one, two or more halogen atoms such as chlorine or bromine, alkyl pyridinium chlorides, alkyl isoquinolinium chlorides and bromides, alkyl lower-alkyl pyrrolidinium chlorides, alkyl lower-alkyl morpholinium chlorides in all of which the alkyl group may have from 8 to 22 carbon atoms and the lower alkyl group may have from 1 to 4 carbon atoms and alkyl phenoxy ethoxy ethyl dimethyl benzyl ammonium chloride in which the alkyl radical may be iso-octyl or nonyl and in which the phenyl radical may, if desired, be substituted by a methyl radical. Various other analogs of these quaternaries may also be employed such, for example, as cetyl dimethyl ethyl ammonium bromide or oleyl dimethyl ethyl ammonium bromide.

In general, the quaternary ammonium compounds useful in this invention are the higher alkyl quaternary ammonium hydroxides, halides (chlorides and bromides), sulfates, methosulfates and the like possessing the following formula:

where R is an alkyl or alkylalkyl radical containing from 8 to 22 carbon atoms or an alkyl phenoxy ethoxy ethyl radical in which R is an alkyl radical containing from 8 to 9 carbon atoms and in which the phenyl radical may be substituted by a methyl group; R' and R'' are methyl or ethyl radicals or members of a heterocyclic ring system such as pyridine, isoquinoline, pyrrolidine and mor-

2

pholine; R''' is a methyl radical or a benzyl group or a substituted-benzyl group such, for example, as a monochlorobenzyl radical or a dichlorobenzyl radical or mixture thereof or a methyl benzyl, dimethyl benzyl, ethyl benzyl, diethyl benzyl, isopropyl benzyl, tertiary butyl benzyl or another benzyl radical containing from 1 to 5 carbon atoms as side chains, either as a single side chain or a multiplicity of side chains including mixtures thereof or a menaphthyl group of hydrogenated menaphthyl group. When R' and R'' are members of a morpholine or pyrrolidine ring, R''' is a methyl, ethyl, propyl or butyl group. When R' and R'' are members of an unsaturated heterocyclic ring such as pyridine or isoquinoline, R''' is the same radical as R''. X in the above formula corresponds to a halide radical such as chloride, bromide or iodide or to any other water-soluble anion such as methosulfate.

In general, we prefer to use such quaternary ammonium compounds which have a phenol coefficient of at least 100 with respect to both *Staphylococcus aureus* and *Salmonella typhosa* at 20° C. when determined by the standard method given in the "Official Methods of Analysis of the Association of Official Agricultural Chemists," ninth edition (1960), page 63 et seq.

The compounds of this invention may be prepared by dissolving the pseudo-acid in question in dilute caustic soda solution to form the sodium salt and mixing this with a solution of a quaternary ammonium salt.

After thorough mixing, the organic product layer is separated from the aqueous layer (as with a separatory funnel) since two distinct phases are formed. Separation may be facilitated by the addition of an organic solvent immiscible with water. The product layer may be washed with water to remove any residual by-product salt or unreacted materials. The solvent, if any, may be evaporated and the product air or vacuum dried to a paste, wax, oil or solid.

It is not necessary to use an aqueous medium. Any solvent or solvent mixture in which the starting materials are soluble will be satisfactory. Non-aqueous solvents facilitate the separation of by-product inorganic salt and reduce the need for vacuum drying to get an anhydrous product. When a non-aqueous medium is employed, it is usually necessary to add a small amount of water to facilitate ionic reaction.

The product may be used, if desired, without drying since any entrapped water is irrelevant to the microbiological activity of the compounds. In other applications, removal of water may be essential for reasons not related to biological activity.

An alternative method for the preparation of compounds especially applicable to the treatment of fabric, ropes, net, woven and non-woven fabric and reticulated or convoluted materials involves a two-step process. In the first step, the material is passed through a bath containing the anionic moiety. Excess solution is removed by methods well known to those skilled in the art. The treated material is then passed through a second bath wherein the concentration of quaternary ammonium compound is such that the material pickup will result in an equivalent amount of quaternary ammonium compound reacting with the anionic moiety, depositing the product in the most intimate way on the surface and in the interstices, convolutions and reticulations of the material.

The method of adjustment of solution concentration to achieve the required pickup is well known to those skilled in the art. The order of treatment may be reversed without affecting the biological activity or durability of the product on the material. The products of this invention may be formulated as water dispersions by dissolving them in a water miscible organic solvent such as

106-18.31
SEARCH ROOM
July 26, 1966

acetone or methanol and diluting with water or by dissolving them in emulsifiable oils such, for example, as sulfonated castor oil or pine oil and diluting with water. In preparing aqueous dispersions, emulsifying agents such, for example, as ethylene oxide condensates of alkyl phenols may be used with or without organic solvents.

It is surprising that the compounds of this invention exhibit high microbiological activity despite their relative insolubility in water. Because of their unusual combination of physical and microbiological properties, they can be used to impart laundry-resistant anti-microbial characteristics to textiles. They can also be used as the active agent in antimildew finishes for textiles which are resistant to leaching with water.

Although the compounds have low water solubility, they are compatible with various organic solvents, plasticizers and high molecular weight compounds. Consequently, they may be incorporated as anti-microbial agents in synthetic resins and plastics. The compounds are compatible with natural and synthetic rubber latices. Therefore, they may be used to prepare bacteriostatic films and molded objects deposited from such latices.

The compounds can be incorporated into cutting and grinding fluids without precipitation. Also, they blend well with non-ionic and anionic surface active agents. In such compositions they retain their microbiological activity.

It will be understood that the properties of the products described herein will vary depending upon the nature of the cationic quaternary ammonium compound used in their preparation as well as the anionic compound reacted therewith.

The chemical, physical and biological properties of the products of our invention make them especially appropriate for the following applications when suitably incorporated in active amounts in an appropriate vehicle, binder, medium or substrate:

- (1) Mildewproofing fabric, canvas, ropes, textiles, awnings, sails, tenting and other woven and non-woven reticulated materials.
- (2) Paint mildewstats.
- (3) Jet plane fuel additive to control growth of micro-organisms.
- (4) Odor preservative agents for clothes and shoes.
- (5) Mildew retardant and odor suppressant for shoes and other leather products.
- (6) Topical antiseptics.
- (7) Antidandruff agents.
- (8) Disinfection agents for hair and gut of man and beast.
- (9) Bacteriostatic furniture dressing.
- (10) Surface finishes for stone, plaster, tile, cement, brick and other inorganic building materials to retard growth of microorganisms, fungi, mold and algae.
- (11) Wool preservative.
- (12) Plant and tree spray to combat fungi.
- (13) Antimycotic agents for soap wrappers.
- (14) Self-sanitizing brushes.
- (15) Mildewproofing agent in and on plastic and film.
- (16) Mildewproofing of cellulosics, cardboard, fibre-board, paper and cordage.
- (17) Contact biostat for application to film, waxes and cloth to preserve cheese, meats and vegetables and other food products.
- (18) Algal inhibition, especially on surfaces and in solution where low foaming is desirable.
- (19) Paper pulp slime control.
- (20) Sanitizing agent for rug, carpet, curtains.
- (21) Egg preservation.
- (22) Adhesive preservation.
- (23) Preservation of latex paints.
- (24) Preservation of metal-working compounds.
- (25) Additives for soap and for both anionic and non-ionic detergents in liquid, bar, powder, bead,

solution and other forms to impart bacteriostatic and fungistatic properties thereto.

- (26) Bacteriostatic agents for household laundry softeners.
- (27) Algastat and bacteriostat in recirculated water for cooling towers, air conditioners and humidifiers.
- (28) Bacteriostat and algastat for flood waters and brines used in secondary oil recovery.
- (29) Fungistat for seed and soil treatment against damping-off.

The microbiological activity of our compounds has been evaluated for microbiological stasis by the Standard Tube Dilution Test, the technique for which is common knowledge to those skilled in the art. A Difco Bacto CSMA broth #0826 was used in the study. This test is used to determine the lowest concentration of microbiologically active compounds which will inhibit the growth of the organisms in question. For a wide range of applications, the inhibition of growth rather than outright kill is satisfactory.

Briefly put, the Tube Dilution Test consists in placing 9 cc. of the CSMA broth in a test tube which is then sterilized in an autoclave. One cc. solution of the microbiologically active compound at an appropriate concentration is added to the test tube which is then inoculated with 0.1 cc. of a twenty-four hour old culture of the organism under study. The test tube is then incubated at 37° C. for forty-eight hours and observed for bacterial growth.

The same procedure is followed for fungi. In such tests, however, the tubes are incubated for fourteen days at a temperature suitable for optimum fungal growth, usually 25° C.

The invention is illustrated by, but not limited to, the following examples:

Example I

A 10% solution of 1-phenyl-1,3 butanedione sodium salt was prepared by dissolving the ketone in sodium hydroxide solution.

An aliquot of this solution containing 0.0326 molecular weight of the compound was mixed with vigorous agitation with a chemically equivalent amount of a 10% aqueous solution of a commercial grade of alkyl dimethyl ethyl-benzyl ammonium chloride (Millmaster Onyx Corporation's "BTC-471" in which the alkyl distribution is 50% C₁₂, 30% C₁₄, 17% C₁₆, 3% C₁₈). The mixture was separated in a separatory funnel and the organic product layer was removed and vacuum dried. Sixteen grams of the alkyl dimethyl ethyl-benzyl ammonium salt of 1-phenyl-1,3 butanedione was recovered as a yellow oil or 95% of the theoretical yield.

When tested by the Standard Tube Dilution Method described above, this product gave the following values for static dilution vs.:

<i>Staphylococcus aureus</i>	-----	10 ⁻⁶
<i>Salmonella typhosa</i>	-----	10 ⁻⁷
<i>Aspergillus niger</i>	-----	10 ⁻⁴

Example II

An aliquot of the solution of the sodium salt of 1-phenyl-1,3 butanedione of Example I containing 0.0326 molecular weight of the compound was vigorously agitated while adding a chemically equivalent amount of a 10% solution of a commercial grade of alkyl dimethyl benzyl ammonium chloride (Millmaster Onyx Corporation's "BTC-824" in which the alkyl distribution is 60% C₁₄, 30% C₁₆, 5% C₁₂, 5% C₁₈). The mixture along with a little benzene was transferred to a separatory funnel wherein two phases separated. The organic product layer was removed and vacuum dried. The alkyl dimethyl benzyl ammonium salt of 1-phenyl-1,3 butanedione was recovered in 91% of the theoretical yield as a yellow liquid.

When tested by the Standard Tube Dilution Method

described above, the product gave the following values for static dilution vs.:

<i>Staphylococcus aureus</i>	-----	10 ⁻⁷
<i>Salmonella typhosa</i>	-----	10 ⁻⁵
<i>Aspergillus niger</i>	-----	10 ⁻⁴

Example III

An aliquot of the solution of the sodium salt of 1-phenyl-1,3 butanedione of Example I containing 0.0326 molecular weight of the compound was agitated vigorously while adding a chemically equivalent amount of a 10% aqueous-alcohol solution of a commercial grade of alkyl isoquinolinium bromide (Millmaster Onyx Corporation's "Isothan Q-75" in which the alkyl distribution is 50% C₁₂, 30% C₁₄, 17% C₁₆, 3% C₁₈). The mixture was heated to evaporate the alcohol, cooled and transferred along with a little benzene to a separatory funnel wherein it separated into two phases. The organic product layer was removed and vacuum dried to a dark brown liquid in 97% yield of the alkyl isoquinolinium salt of 1-phenyl-1,3 butanedione.

When tested by the Standard Tube Dilution Method described above, this product gave the following values for static dilution vs.:

<i>Staphylococcus aureus</i>	-----	10 ⁻⁶
<i>Salmonella typhosa</i>	-----	10 ⁻⁵
<i>Aspergillus niger</i>	-----	10 ⁻⁴

Example IV

A solution of the sodium salt of 2,4-pentanedione containing 0.050 molecular weight of the compound was reacted with a chemically equivalent amount of an aqueous-alcohol solution of a commercial grade of dodecyl dimethyl menaphthyl ammonium chloride (Millmaster Onyx Corporation's "BTC-1100"). The alcohol was evaporated off and the organic product layer was removed and vacuum dried. The dodecyl dimethyl menaphthyl ammonium salt of 2,4-pentanedione as a solid was recovered in the theoretical yield.

Example V

Ethyl acetoacetate was dissolved in dilute aqueous sodium hydroxide to form the sodium salt. An aliquot of this solution containing 0.240 molecular weight was reacted with the chemically equivalent amount of the dodecyl menaphthyl ammonium chloride of Example IV. Benzene was added and dried to yield the dodecyl me-

naphthyl ammonium salt of ethyl acetoacetate as a yellow oil.

We claim:

1. Alkyl dimethyl ethyl-benzyl ammonium enolate of 1-phenyl-1,3 butanedione.
2. Alkyl dimethyl benzyl ammonium enolate of 1-phenyl-1,3 butanedione.
3. Alkyl isoquinolinium enolate of 1-phenyl-1,3-butanedione.
4. Dodecyl dimethyl menaphthyl ammonium enolate of 2,4-pentanedione.
5. Dodecyl menaphthyl ammonium enolate of ethyl acetoacetate.
6. A quaternary ammonium ketonic enolate having the structure:

25 wherein Z is the cation of a quaternary ammonium compound having a phenol coefficient of at least 100 with respect to *Staphylococcus aureus* and *Salmonella typhosa* at 20° C. and having at least one alkyl group of 8 to 22 carbon atoms on the quaternary nitrogen; R is selected from the group of alkyl and halogenated alkyl; R' is selected from the group of hydrogen, halogen, carboxyalkyl and carboxyaryl; and R'' is selected from the group of alkyl and alkoxy.
